UNITED STATES PATENT OFFICE

JOSEPH E. GADBOIS, OF SPRINGFIELD, MASSACHUSETTS

CLOTH SPREADING AND PILING MACHINE

Application filed April 16, 1928. Serial No. 270,384.

This invention relates to a cloth measuring and cutting machine and has for its primary object the provision of a machine of a semi-automatic type combining a plurality of mechanisms whereby a predetermined length of cloth may be mechanically fed over a cutting table into proper position to be cut; mechanism automatically functioning to interrupt operative connection between the cut cloth and the machine and to operate to elevate portions of the machine for another cycle of operation.

Another object of the invention is the provision of mechanism for automatically gripping a length of cloth at predetermined intervals and drawing the cloth over a cutting table, the cloth automatically actuating certain parts to release itself from the mechanism upon reaching a predetermined position.

Another object of the invention is the provision of a plurality of sets of mechanism correlated and co-functioning to feed and cut a plurality of lengths of cloth into stacked formation upon a cutting table.

A distinguishing feature of the machine is the automatic control for the various mechanisms whereby the mechanisms are automatically and periodically set into operation to perform their necessary functions in the feeding of cloth across a cutting table and the stacking thereof.

A feature of the invention is the feeding mechanism incorporating a plurality of gripping devices capable of automatic gripping engagement with the cloth for drawing the cloth across the table and capable of automatic releasing so as to immediately disconnect the mechanism from the cloth when the latter has been drawn the required distance over the cutting table.

Besides the above my invention is distinguished in the combination design and correlation of mechanisms and combinations of mechanisms whereby any number of lengths of cloth may be automatically drawn over a cutting table and stacked in a perfectly smooth arrangement.

With these and other objects in view, the invention will be better understood from the

following detailed description taken in connection with the accompanying drawings, wherein

Figure 1 is a side elevation of the complete machine,

Figure 2 is a top plan view,

Figure 3 is a cross sectional view on the line 3—3 of Figure 1,

Figure 4 is a cross sectional view on the line 4—4 of Figure 1,

Figure 5 is a sectional view on line 5—5 of Figure 1,

Figure 6 is a cross sectional view on the line 6—6 of Figure 1,

Figure 7 is a detailed sectional view 65 through the cutting mechanism,

Figure 8 is a detailed side elevation of a portion of the control mechanism,

Figure 9 is a cross sectional view of a part 70 of the feed mechanism and associated parts,

Figure 10 is a cross sectional view of the feed mechanism and component parts,

Figure 11 is a fragmentary side elevation 75 of a part of the feed mechanism,

Figure 12 is a sectional view of the forward part of the machine taken on the line 12—12 of Figure 2, and Figure 13 is a sectional view of the remaining part of the machine taken on the line 12—12 of Figure 2.

Briefly stated, the invention consists basically of a material supporting structure upon which the roll of cloth is mounted and fed to the machine; a table structure over which the cloth is extended for a cutting operation; feed mechanism for drawing the cloth over the cutting table; elevating mechanism for raising the feed mechanism the required elevation to accommodate stacking of the cut cloth; drive mechanism for driving the various associated mechanisms periodically in timed relation; and releasing mechanism co-functioning with associated mechanisms to control and regulate the relative operations of the various mechanisms.

Broadly stated, the functioning of the mechanisms just mentioned according to time requirements are as follows: first, the feed mechanism is set into operation for drawing the cloth the required distance across the cutting table; then, the main control mechanism

is actuated by the cloth when the latter has reached a predetermined position along the cutting table to discontinue the operation of the feed mechanisms; then the releasing mechanism operates to release mechanical engagement of the feed mechanism with the strip of cloth previously fed over the cutting table; then the elevating mechanism operating to elevate the feed mechanism the required elevation to accommodate stacking of the cut cloth and finally the auxiliary control functioning to restore the necessary parts to neutral position for enabling the machine to again pass through a cycle of operation.

Material supporting structure.—This material supporting structure consists of a supporting frame 1 and a plurality of feed rolls 2 supported thereby and properly positioned to feed the web 3 of the cloth toward the cutting machine as it is fed off the cloth roll 4.

The upper set of feed rolls have each a yieldable surface 5 to more effectively engage the web with one of the rollers adjustably mounted and spring pressed as indicated at 25 6 so as to assure positive engagement between the peripheral surface of the rolls and the traveling web and further to provide the necessary mechanical action to draw the web of cloth from the roll 4 and over the various feed rolls to a position contiguous the receiving end of the feeding mechanism. The shaft 5^a which carries the lower roll of the upper set of feed rolls is provided with a pulley 7^a over which travels a belt 7. A 35 double pulley 7^b is mounted upon the frame 1 and the belt 7 also passes over the smaller pulley thereof, whereas the larger pulley is driven by a belt 7^c, which latter extends over a pulley 73 carried by the driven shaft 11 (see Figure 3). A main drive shaft 8 is also journaled in suitable bearings supported by the frame 1 and has connected thereto a double drive pulley 9 from which it receives its power. The driven shaft 11 is to be operatively connected to the drive shaft 8 by means of a sprocket chain drive 10 in a manner to be later described so that upon rotation of the driven shaft 11, the upper feed rolls will be caused to revolve through the belt and pulley drive connections as previously described, whereupon the web of cloth will be drawn from the roll 4 and fed to the cutting table.

Table structure.—The table structure may 55 be of any suitable design commercially known as a cutting table and provided with a cutting top 12 and legs 13 for supporting the top at the required elevation. Properly associated with this cutting table is the feed mechanism, elevating mechanism, driving mechanism and releasing mechanism herein-after described.

Feed mechanism.—The feed mechanism 65 consists of tracks or side frames 14, one on each side of the table and mounted to have

vertical adjustable movements in the manner hereinafter described. Each track 14 is of U-shaped formation in cross section to provide a channel 15 in which travels an endless drive chain 16 passing around sprockets 17 placed upon counter shafts 18 disposed at opposite ends of the table. Thus, it will be appreciated that the drive chains are positively driven in unison thereby assuring positive uniform feed of the cloth across the table. Secured at spaced intervals to one of the drive chains are clips 19 of a design to periodically engage the longitudinal edge portion of the cloth at predetermined intervals so as to be capable of drawing the cloth across the cutting table in a manner as to not wrinkle the latter and to assure the flat contact of the cloth with the surface of the table.

These clips 19 may be of any suitable design but preferably of a spring actuated type each comprising a stationary gripping jaw 21 secured to and carried by the drive chain 16 and a pivotally mounted jaw 22 normally held into gripping engagement with the stationary jaw so as to automatically function to grip the cloth when the jaws have been opened and then released. The drive chains are provided with connectors 23 which are oppositely arranged and each comprise a block 24 secured to and adapted to travel with the chains, each block having a vertically extending pin for receiving the recessed ends of a clamp bar 24 whereby when this clamp bar is attached to one set of connectors, the bar will be caused to travel over the table 12 with the chains 16. This clamp bar is provided for clamping the transverse edge portion of the web 3 of cloth and to bring about a more effective engagement between the clamp bar 24 and the cloth, I have shown the former provided with a plurality of pins 25 adapted to pierce the cloth in a direction to enable the clamp bar to be readily removed when the bar is to be disconnected from the cloth.

I will now describe the drive mechanism a component part of the feed mechanism and of a novel design and construction to enable uniform driving of the chains and to enable cessation of the operation of the said chains under predetermined requirements. This mechanism consists of gears 26 operatively associated with certain of the sprockets 17 and driven by the worm gears 27 splined to but 115 slidably mounted on the drive shafts 28, which are in turn slidably mounted in tubular shafts 29 carrying bevel gears 30 operatively associated with the main driving mechanism hereinafter described.

As far as I have proceeded, it will be appreciated that the drive chains may be driven the required interval of time to properly distribute a length of cloth over the cutting table and said mechanism may be raised vertically

due to the sliding connection between the worm gears and associated shafts and the driving connection between the tubular shafts and the worm gear shafts. Thus, it will be appreciated that stacking of the cloth can be accommodated without in any way interfering with the effective operation of the feed mechanism for drawing the cloth across a pile or stack of cut material.

Included in the feed mechanism is a guide structure 31 arranged at the receiving end of the cutting table or feed mechanism and in one of its forms consists of a pair of guide plates 32 and 33 having a hinged connection 34 with each other so as to facilitate the feeding of the web of material between the plates. Secured to and projecting from the table are a pair of brackets 31' which support the guide roller 32', the latter extending across the feeding end of the guide plates 32 and 33. The hingedly supported plate 33 is provided with a handle 33' whereby the operator may separate the plates for threading the web 3 therethrough. The outer or free end of the plate 33 is provided with a plurality of notches 35 adapted to receive the vertically extending pins 25 of the clamp bar 24 so that the clamp bar may, at the start of each cloth laying operation, be placed below the plate 33 and the cloth attached by hand to the pins 25. When the machine is again started, the chains 16 will draw this bar 24 from the plate 33 across the table 12 until the bar 24 strikes the bar 39 at which time the feed mechanism will be stopped. After each layer of cloth is spread over the table 12 in the required length, a cutting device is brought into play for severing such layer of cloth from the web 3. This cutting device comprises a grooved plate 36' mounted upon the table 12 having the groove thereof extending laterally across the table and slightly in advance of the plates of the cutting structure 31 for receiving the cutting edge of the knife 37 when the latter is in its lowermost position. This knife 37 is carried by a frame 38^b slidably mounted in the supports 37^a secured to and projecting from the plate 36' and is normally held in an elevated position as is better shown in Figure 6 of the drawing by means of the coil spring 36^b. A handle 38 is fulcrumed as at 38^a to one of the supports 37^a and has pivotally connected thereto as at 36, the knife frame 38^b so that the operator in pressing down upon the outer or free end of this handle will cause the knife to cut each layer of cloth from the web 3.

Also included as a component part of the feed mechanism is a main control mechanism so designed and positioned as to be automatically actuated when a length of cloth has been moved the required distance across the cutting table. That is to say, a projecting portion of the main control mechanism is

positioned to be struck by the transverse edge of the cloth for giving movements thereto for shifting associated parts to stop further movements of the feed mechanism and to establish cooperative relation between various other mechanisms to enable the machine to perform additional functions.

This main control mechanism comprises a shifter or bar 39 which latter may extend through either one of the openings 39' formed within the table top 12 according to the length of the layers of cloth to be cut in order to project within the path of travel of the clamp bar 24 so that this bar 39 may be shifted for causing the feed mechanism to be stopped. Pivotally supported as at 40, below the openings 39' formed within the table, are levers 40^a and 40^b and the lower ends of these levers are connected to a bar 41. The upper ends of these levers 40^a and 40^b are each provided with a socket in which may be seated the bar or shifter 39. If layers of cloth of short lengths are desired, the bar 39 is seated within the socket of the lever 40^a as is better illustrated in Figure 1 of the drawings, but if layers of cloth of longer lengths are required the bar 39 will be seated within the socket of the lever 40^b. When the clamp bar 24 strikes this bar 39 the levers 40^a and 40^b will be swung upon their pivotal connections for shifting the link 41 and the opposite end of this link 41 is connected to a clutch lever 42. This clutch lever 42 is pivotally supported upon one of the legs 13 of the table as is better illustrated in Figure 5 and is operatively associated with the control clutch of the driving mechanism to be later described, so that the cloth feeding mechanism may be disconnected from the driving mechanism immediately after each layer of cloth has been placed upon the table 12.

Releasing mechanism.—The releasing mechanism in this particular showing consists of a release bar 43 of the required length to simultaneously engage all of the active clips for simultaneously releasing engagement of the clips with the longitudinal edge portion of the cloth. To accomplish this desired result, the release bar is arranged in parallel relation with the upper jaws of the clips so that when this bar is depressed the upper jaws will be swung about their pivots against the action of the associated springs for opening the jaws. Secured to the opposite ends of one of the movable tracks 14 are the bearings 45, each having slidably mounted therein a vertically extending shaft or bar 44 which latter are formed with the opposite ends of the clip releasing bar. Springs 46 associated with the shafts 44 normally hold the release bar in an elevated position out of engagement with the clips and for the purpose of depressing the bar in opposition to the resiliency of the springs 46, I

provide the automatic release device now to be described. This device consists of levers 47, each pivoted at an intermediate point to the vertically movable track frame 14 and with one end directly connected to the lower end of the associated bar or shaft 44 and its other end free and operatively associated with a cam 48 fixed to a release shaft 49 supported by the hangers 50 and further carries stops 51 provided with notches 52 operatively associated with pins 53 carried by the tracks. Secured to the release shaft is a crank arm 54 having a flexible connection with the rack bar 55 that is in turn operatively associated 10 with the mutilated gear 56 upon the counter shaft 57. This counter shaft carries a relatively large sprocket 58 operated by a drive chain 59 which is in turn operatively associated with the drive mechanism hereinafter described.

As far as I have proceeded, it will be appreciated that in the operation of the counter shaft 57 by the sprocket 58, the mutilated gear 56 will periodically actuate the rack bar 55 for, swinging the crank arm 54 in the required direction to give movement to the release shaft. This movement of the release shaft will cause the cams to operate the associated levers which in turn subject the shafts 44 of the release bar to a downward sliding movement for bringing the release bar into operative engagement with all of the clips associated therewith. Thus, it will be appreciated that in an automatic manner I am able 25 to simultaneously operate all of the clips that engage the cloth for disconnecting the clips from the cloth in a manner as to not disturb the smooth engagement of the cloth with the surface of the table.

Driving mechanism.—This drive mechanism consists of the heretofore mentioned transmission shaft 11 carrying a pulley 73 having a drive connection with the driving means of the material supporting structure. 40 In addition, the transmission shaft 11 carries a slidably mounted sprocket 74 having a drive chain connection 10 with the main shaft 8. Associated with the sprocket 74 are the clutch members 76 and 77, the former operatively associated with a clutch member 78 fixed to the transmission shaft and the latter 78' operatively associated with a loose gear 79 operatively associated with a second gear 80 directly connected to a sprocket 50 wheel 81 around which is trained the drive chain 59. To complete the driving mechanism, I provide a controller 82 positioned to be manually operated and this controller is secured to the clutch lever 42 hereinafter described and thus it will be appreciated that this clutch lever 42 can be either manually operated by the controller 82 or mechanically by the link 41 of the main control mechanism or by a slide bar 83 that is operatively 65 associated with the cam 84 fixed to the shaft

carrying the mutilated gear. This slide bar is normally held in a predetermined position by a spring 85 so that when the mutilated gear has made a complete revolution, the finger will engage the slide bar for moving 70 the same the required distance to actuate the clutch lever 42.

The tracks 14 are supported by the rack bars 60 which latter are slidably supported in suitable bearings carried by the brackets 61^a secured to the legs 13 of the table. Also journaled in suitable bearings upon these brackets 61^a are the transversely arranged shafts 62, each carrying suitable gears 61 meshing with the rack bars 60. These shafts 80 are also provided with sprocket wheels 63 connected by the sprocket chain 64 whereby the shafts 62 may be rotated together. A crank handle 72 is also connected to one of the shafts 62 whereby they may be manually 85 rotated for elevating the tracks 14 to the required positions in order that the cloth may be laid in stacked formation upon the table 12. A ratchet wheel 66 is also keyed to one of the shafts 62 and is adapted to be 90 engaged by a pawl 70 carried by the rod 69 whereas the opposite end of this rod 69 is provided with a pawl 71 adapted to be engaged by a lug 72 carried by the sprocket wheel 58 so that upon each complete revolution of the wheel 58, the rod 69 will be caused 95 to slide in one direction whereat the ratchet wheel 66 will be caused to move one notch which is sufficient to rotate the shafts 62 and cause the track 14 to be raised at a height to 100 accommodate the next layer of cloth to be placed upon the table 12. This rod 69 is supported in suitable bearings carried by the table and a coil spring 69^a is provided for normally retaining the pawl 70 in engagement 105 with the teeth of the ratchet wheel whereas the coil spring 9^b retains the bar 69 in a position whereat the pawl 70 will be normally retained out of engagement with the teeth of the ratchet wheel 66. Also, pivotally supported upon one of the brackets 110 61^a carried by the table is a pawl 67 normally held in engagement with the teeth of the ratchet wheel 66 in order to prevent the same from rotating in an opposite direction where- 115 at the tracks 14 and the mechanism carried thereby will be lowered. As the tracks 14 are raised, the pawl 67 will retain the same in their raised positions and connected to this pawl is a handle 68 whereby the operator may release the same from engagement 120 with the ratchet wheel 66 in order that the tracks 14 may be lowered.

Operation.—To start the machine it is necessary to draw the web of cloth from the roll 125 in position to dispose the edge portion of the web contiguous to the notches of the clamp plate 33 so that the pins of the clamp bar 24 may be inserted into the cloth and the clamp bar rigidly connected to the drive 130

chain through the medium of the connectors 23. When this has been accomplished, operation of the controller 82 will throw the slide sprocket of the transmission shaft into engagement with the clutch element secured to the transmission shaft which causes the transmission shaft to rotate and as this transmission shaft carries bevel gears 86 associated with the bevel gears 30 on the tubular shafts it will be appreciated that the tubular shaft 29 will be caused to rotate carrying with them the shafts 28 carrying the worm wheels 27 which through their meshing relation with the associated gears causes the sprocket wheels 17 to operate the drive chains 16. As the drive chain travels, the clips 19 will successively engage a cam device 87 for momentarily opening a clip for snapping engagement with the cloth at a point contiguous to the feed plates. This engagement of the clips successively with the edge portion of the cloth assures the neat pulling of the cloth over the surface of the table, until the cloth has reached a predetermined position whereupon it will engage the shifter 39 for actuating the same the required distance to shift the sprocket wheel 74 out of engagement with its previously associated clutch element 78 on the transmission shaft. Upon the shifter 39 being fully actuated the transmission shaft sprocket wheel will be thrown into operative engagement with the other associated clutch element 78' for actuation of the gear 79 engaging gear 80 which in turn has an operative connection with the drive chain 59. As the chain 59 is trained over the sprocket 58, it will be appreciated that the mutilated gear 56 is rotated the required distance to elevate the rack bar 55 for the manipulation of the releasing mechanism. This is brought about by the inner engagement of the cams 48 with the levers 47 which have a pivotal connection with the bars 44 of the release bar thereby depressing the release bar the required distance to simultaneously manipulate all of the clips that are in engagement with the cloth. This simultaneous releasing of the clips completely disconnects the feed mechanism from the cloth with the exception of the clamp bar 24 which can be released manually. Subsequently to the operation just set forth, the sprocket wheel 58 has rotated the required distance to bring the lug 72 into engagement with the pawl 71 for sliding the slide bar 69 the required distance to actuate the ratchet wheel 66 the required degree to elevate the feed mechanism through the associated elevating mechanism. Upon completion of each cloth laying and feed mechanism elevating operation, the sprocket wheel 74 is moved to a neutral position whereat the driven shaft 11 will be stopped and in order to automatically stop the feeding and elevat-

ing mechanism at the completion of each operation, the clutch lever 42 has connected thereto a spring actuated rod 83. Keyed to and carried by the shaft 57 is a pin 84 which latter is adapted to engage one end of this rod 83 so that upon each complete revolution of the shaft 57, the cam 84 will engage the rod 83 for exerting a pull thereupon against the tension of the spring 85 so that the clutch carried by the sprocket wheels 73 will be moved and retained in a neutral position and out of engagement with the clutch members 78 and 78'. It is of course to be understood that after the length of cloth has been properly passed over and deposited upon the top of the table, it is only necessary to manipulate the cutting mechanism for severing the length of material from the roll to enable another length of material to be engaged by the feed mechanism and drawn over the previously cut cloth.

It is of course to be understood that various other forms of material supporting structures may be designed to be associated with my novel type of feeding mechanism and besides various other types of feeding mechanism may be used in conjunction with my novel type of elevating mechanism and further, the design co-relation and manipulation of various individual parts of the machine may be designed and changed in various other ways than illustrated and therefore, I do not desire to be limited in protection in any manner whatsoever except as set forth in the following claims.

I claim:

1. A cloth measuring and cutting machine comprising a material supporting structure, a table extending therefrom, feed mechanism cofunctioning with the supporting structure to feed material across said table, cutting mechanism operatively positioned upon the table for cutting the material in predetermined lengths, and means for elevating the feed mechanism periodically.
2. A cloth measuring and cutting machine comprising a cutting table, material feeding mechanism associated therewith, means operatively positioned upon the table for cutting the material into predetermined lengths and elevating mechanism co-functioning with the feeding mechanism to interrupt the operation of the feed mechanism and raise the latter a predetermined height.
3. A cloth measuring and cutting machine comprising a cutting table, material feeding mechanism having adjustable relation with said table to be elevated vertically by step by step movement and raising mechanism periodically functioning according to the operation of said feeding mechanism to periodically subject the feeding mechanism to an elevating movement.
4. A cloth measuring and cutting machine comprising a cutting table, mechanism for

feeding material over said table, elevating mechanism for the feeding mechanism having certain parts so disposed as to be operated by the traveling material whereby periodic operation of the elevating mechanism will periodically discontinue operation of the feeding mechanism and periodically elevate the same.

5. A cloth measuring and cutting machine comprising a cutting table, drive mechanism, cloth feeding mechanism, elevating mechanism for the cloth feeding mechanism and positioned to be intermittently operated by the traveling material to intermittently control the operation of the feeding mechanism and regulate the elevations thereof, said elevating mechanism co-functioning with said drive mechanism to automatically control the operative connection of the drive mechanism with the feed mechanism.

10. A cloth measuring and cutting machine comprising a cutting table, a material supporting structure, feeding mechanism adjustably related with the cutting table, and means for elevating said feed mechanism above the cutting table by a step by step motion whereby the material may be placed thereupon in stacked formation.

15. A cloth measuring and cutting machine comprising a cutting table, a material supporting structure, feeding mechanism adjustably related with the cutting table to be elevated above the cutting table by a step by step motion, cutting mechanism adapted to be manually operated and associated with said feeding mechanism, an elevating mechanism for giving elevating movement to said feeding mechanism and means operable by the material when a predetermined length of 20 the material has been positioned upon the cutting table for causing said elevating mechanism to be operated whereby an elevating movement may be given said feed mechanism.

25. 8. A cloth measuring and cutting machine comprising a cutting table, feed mechanism associated therewith and including gripping means for gripping an edge portion of the material for feeding the same over the cutting table, elevating mechanism for the feeding mechanism including a releasing structure operatively associated with said gripping means to intermittently release the same in accordance with the distance of travel of the material over the cutting table.

30. 9. A cloth measuring and cutting machine comprising a cutting table, drive mechanism, feeding mechanism having a releasable drive connection with said drive mechanism, elevating mechanism for raising the feed mechanism intermittently relative to the work surface of the cutting table and means under the control of the raising mechanism co-functioning with the releasable drive connection to render the feed mechanism inoperative

during the operation of the raising mechanism.

35. 10. A cloth measuring and cutting machine comprising a work table, feed mechanism including a plurality of clips adapted to grip the cloth at predetermined intervals to feed the same over the cutting table, a cloth cutting mechanism for intermittently raising the cutting mechanism including a control device associated with the cutting table to be operatively engaged by the material when the latter has been fed over the work table the required distance, such control device adapted to set the elevating mechanism into operation and discontinue operation of the feed- 40 mechanism.

45. 11. In a cloth measuring and cutting machine, cloth feeding mechanism consisting of a pair of drive chains, a clamp for securing the drive chains to the edge portion of the cloth, a plurality of individual clips secured to one of the chains at predetermined intervals for intermittent engagement with the cloth and releasing mechanism having a timed operative relation with the traveling cloth to be operatively engaged by the cloth when the same has traveled a predetermined distance whereby said clips will be released from the cloth.

50. 12. In a cloth measuring and cutting machine, cloth feeding mechanism including guide plates through which the cloth travels and a clamp bar for clamping engagement with the transverse edge of the cloth, a plurality of cloth engaging devices adapted to engage the longitudinal edge portion of the cloth for feeding the cloth in a predetermined direction, automatically operating releasing mechanism adapted to simultaneously release all of the clips from engagement with the cloth when the latter has been moved a predetermined distance.

55. 13. In a cloth measuring and cutting machine, a cutting table, feed mechanism having a vertical adjustable relation with the cutting table, power mechanism for automatically elevating said feed mechanism when the cloth has been moved a predetermined distance across the cutting table, and manually operated mechanism for elevating the feed mechanism independently of said power mechanism.

60. 14. A cloth measuring and cutting machine comprising drive mechanism, a cutting table, feeding mechanism having a shiftable drive connection with said drive mechanism, raising mechanism having a shiftable drive connection with said drive mechanism and an operative connection with said feed mechanism to intermittently raise the latter and control mechanism for automatically shifting the drive connection between the feed mechanism and the drive mechanism and between the elevating mechanism and the drive mechanism, in accordance with the distance of 65

travel of the cloth across the cutting table.

15. A cloth measuring and cutting machine comprising drive mechanism, a cutting table, feeding mechanism having a shiftable drive connection with said drive mechanism, raising mechanism having a shiftable drive connection with said drive mechanism and an operative connection with said feed mechanism to intermittently raise the latter, control mechanism for automatically shifting the drive connection between the feed mechanism and the drive mechanism and between the elevating mechanism and the drive mechanism, in accordance with the distance of 10 travel of the cloth across the cutting table and manually operated device for intermittently raising said feed mechanism independent of said raising mechanism.

16. In combination with a cloth feeding 20 mechanism, elevating mechanism therefor consisting of power mechanism having a direct drive connection with said elevating mechanism and disposed to be engaged by the traveling cloth to control the operation 25 thereof, and a ratchet feed device for elevating said feed mechanism independently of said elevating mechanism.

17. In combination, a cutting table, feeding mechanism mounted upon the cutting table to have vertical adjustment, rack bars secured to the feed mechanism, power mechanism including gears operatively associated with said rack bars and a control device associated with the cutting table to be engaged 35 by the traveling cloth to be set into operation thereby for controlling the action of the feeding mechanism.

In witness whereof I have hereunto set my hand.

JOSEPH E. GADBOIS.
